UNITED STATES PATENT OFFICE.

DORRENCE WILLIAM LEPPERT, OF NEW YORK, N. Y.

TELEPHONE ATTACHMENT.

1,042,933.

Specification of Letters Patent. Patented Oct. 29, 1912.

Application filed May 5, 1911. Serial No. 625,142.

To all whom it may concern:

Be it known that I, DORRENCE W. LEPPERT, a citizen of the United States, and a resident of the city of New York, borough 5 of Manhattan, in the county and State of New York, have invented a new and Improved Telephone Attachment, of which the following is a full, clear, and exact description.

10 This invention relates to a new and improved attachment adapted to be secured to a telephone instrument, so that a strip of writing material, such as paper, can be unrolled, and any conversation coming over 15 the telephone taken down.

An object of this invention is to provide a simple device adapted to be supported on the telephone instrument, which in turn supports a roll of paper in such a position that 20 it can be drawn up over a supporting surface, so that messages of any length can be written on the paper, and when finished, can be cut from the body of the paper by a simple twist, bringing the paper in engagement 25 with the serrated edge of the support.

A further object of this invention is to provide a memory tablet attachment for a telephone instrument, which can be readily attached and detached, which will be simple 30 in construction, inexpensive to manufacture, strong and durable, and which will guide the paper in a simple and convenient manner.

These and further objects, together with 35 the construction and combination of parts, will be more fully described hereinafter and particularly set forth in the claims.

Reference is to be had to the accompanying drawings forming a part of this specification, in which similar characters of reference indicate corresponding parts in all 40 the views, and in which—

Figure 1 is a perspective view showing my device attached to a telephone instrument; 45 Fig. 2 is a vertical longitudinal section; Fig. 3 is a top plan view of the attachment detached from the telephone instrument; Fig. 4 is a fragmentary vertical transverse section; and Fig. 5 is a section on the line 5—5 50 of Fig. 3.

Referring more particularly to the separate parts of this invention as embodied in the form shown in the drawings, 1 indicates my attachment, which is adapted to be se-

cured to the standard of a telephone instrument, indicated at 2. The attachment includes a supporting platen 3, which is adapted to form a smooth surface for a strip of paper, indicated at 4. The sides 5 of the supporting platen 3 are preferably a little higher than the intermediate body portion, as indicated in Fig. 4, so as to form guides which prevent the strip of paper 4 slipping off sidewise.

As shown in Figs. 1 and 2, the supporting 65 platen 3 is preferably convex at its lower end, so as to permit the paper to readily pass over the same, and is provided at its upper end, as will be seen by reference to Fig. 3, with a serrated edge indicated at 7, so that a strip of the paper on which the notes have been made can be readily severed from the body portion thereof.

The supporting platen 3 is secured on the standard 2 by a detachable bracket 8, which 75 may be of any suitable form, but in this instance is shown in the form of a member bent from a single strip of wire. The bracket 8, as shown, is provided with a loop 9, circular in form to engage the cylindrical 80 standard 2, and from one side of which extends parallel legs 10. In order to get the necessary leverage or foothold to get a firm grasp on the standard 2, the loop 9 is corrugated or zig-zagged up and down, as is 85 clearly illustrated in Figs. 1 and 2. The platen 3 is provided with a plurality of apertures 11 and 12, in which the legs 10 can be detachably inserted to secure the platen to the bracket; as shown in the drawings, the apertures 11, 12, are opposite each other and in alinement, such relative position of the parts, however, being capable of modification in order to adapt it to different uses. As will be seen by reference to Fig. 1, 95 these legs are provided with a dip intermediate their ends, so that they can pass through the aperture 11 under the platen 3, and up through the aperture 12. The outer ends of the legs 10 are formed with extending lugs 13, so that they can grip the upper side of the platen 3 and form a secure connection. The metal of the platen 3 may be rabbeted at this point, so that the lugs 13 will not project too far above the surface of 100 the platen 3.

It is to be noted that the bracket 8 is made of springy material, so that the legs 10 tend 105

to normally spring away from each other, and yet are confined by the limits of the apertures 11 and 12, so that when once in position, the bracket 8 will firmly grip the standard 2.

The paper 4 is preferably supported on a reel 14, located subjacent the platen 3, adjacent the lower end thereof where the platen 3 curves upwardly to form the convex above mentioned. The reel 14 may be supported in any well known manner on the platen 3, but preferably is held in position by a holder 15. The holder 15 not only supports the reel 14, but also engages the top of the strip of paper passing over the platen, adjacent the upper end of the support, so as to secure the strip of paper in its stretched position over the platen, without wrinkles. In this instance, the holder 15 is shown as being somewhat U-shaped, with a cross bar 16 extending above the platen, and sides 17 extending below the platen, the ends of the sides being turned over to form stub shafts 18, which are pivotally mounted on the platen 3, as by engaging in depressed loops 19 stamped out of the body of the platen. The sides 17 comprise two angularly-disposed reaches 20 and 21, connected by a loop 22, which forms a bearing for the shaft 23 of the reel 14.

In order that the holder may come in close juxtaposition to the paper 4, the sides 5 of the platen 3 are cut away at 24 thereby forming notches, to permit the holder to enter at these points, and yet maintain the sides 17 thereof beneath the platen. It will be seen from this that the weight of the holder 15, and the reel 14, will normally tend to bring the bar 16 in intimate contact 40 with the paper 4, and thus hold it securely in position.

The utility of the device will be readily understood when taken in connection with the above description. The device is adjusted in the position indicated in Fig. 1, with a strip of the paper over the platen 3, so that when a conversation is had over the telephone, notes, or even the whole conversation, can be transcribed onto the sheet of 50 paper 4. It is immaterial how long the conversation is, as the strip of paper can be continually adjusted so as to bring successive portions thereof over the platen 3, giving a sheet of any desired length. When 55 the notes have been finished, the portion of the sheet written upon can be severed from the body thereof by a slight downward movement, causing the serrated or toothed edge 7 to cut the paper, as indicated in Fig. 60 1. The very act of removing the portion written upon brings a fresh surface above the platen 3, ready for a subsequent memorandum.

It will be seen that there is thus provided a simple and efficient device, which

can be readily attached to and detached from a telephone instrument, and which will be readily accessible and convenient to use.

While I have shown one embodiment of my invention, I do not wish to be limited to the specific details thereof, but desire to be protected in various changes, alterations and modifications which may come within the scope of the appended claims.

Having thus described my invention, I claim as new and desire to secure by Letters Patent:—

1. The combination with a suitable platen, a holder connected thereto and to the under side thereof, the holder comprising a bar 80 extending transversely of the platen and above it, reaches connected to the bar, each of the reaches comprising a loop, means positioned in the loops for rotatably holding a roll of paper, the paper passing over the 85 top of the platen and beneath the bar, the weight of the paper and the holder maintaining the said bar in contact with the top side of the paper on the platen.

2. The combination with a platen of a 90 holder pivotally mounted on one end and adjacent the under side thereof and freely engaging the said platen at its opposite end and upper side, the said holder being provided with means for supporting paper 95 holding means adjacent one end of the said platen and beneath the same, the paper extending up over the platen and beneath a portion of the holder whereby it is positioned on the platen.

3. The combination with a platen having a convex end and loops adjacent the said end, of a holder having one end of each side thereof pivotally engaging in the said loops, the other end of the holder comprising a 105 cross-bar, the said cross-bar lying adjacent the opposite end of the platen and above the same, the holder being provided with means for supporting paper holding means beneath the platen, the said paper passing over the 110 platen and beneath the said cross-bar, the weight of the roll of paper maintaining the cross bar in engagement with the paper on the platen.

4. The combination of a suitable platen 115 having a portion removed at each side ~~there~~ of adjacent one end in order to form notches, with a holder comprising a cross bar and sides, one end of each side being pivotally engaged with the platen, the cross bar lying on top of the platen, opposite portions of the holder engaging in the said notches, the holder being provided with means for supporting paper holding means, whereby the weight of the paper when supported by 125 the holder will maintain the cross bar closely adjacent the top of the platen.

5. The combination of a suitable platen having a convex lower end and a serrated upper end, opposite side portions of the 130

platen being cut away adjacent the upper end thereby forming notches, loops carried by the platen adjacent the convex end, a holder comprising an intermediate cross-bar and angularly-disposed reaches, one end of each reach being engaged in the said loops, an intermediate portion of each reach providing a bearing for holding a suitable reel of paper, the said cross-bar lying on top of the platen with a portion of each reach adjacent the cross bar engaging in the said notches whereby the holder is maintained in position on the platen with the cross bar in engagement with the paper passing thereover.

6. The combination of a platen having its intermediate portion depressed, the lower end of the platen being convexly curved, the upper end of the platen and at opposite sides thereof being removed for a suitable distance thereby forming notches, a holder

comprising an intermediate cross-bar, reaches extending from each end of the cross-bar, one end of each reach being pivotally supported adjacent the convex end of the platen, each of the reaches suitably supporting a roll of paper beneath the platen, the said cross-bar extending across the top of the platen with the paper from the roll passing through the depressed intermediate portion of the platen, the cross-bar resting on the said paper, the upper ends of the said reaches being positioned in the said notches whereby the relation of the holder with respect to the platen is maintained.

In testimony whereof I have signed my name to this specification in the presence of two subscribing witnesses.
